TOY REGISTER BANK

Jacob Farber, New York, N.Y.

Application February 23, 1950, Serial No. 145,735

1. Claim. (Cl. 235—100)

1

This invention relates to a cash register construction.

It is an object of the present invention to provide a simple cash register construction whereby registry of the coins inserted into a slot thereon will be automatically made and wherein a predetermined number of such coins within the construction will be automatically tallied and will permit the removal of a slide to permit the construction to dispense the coins.

It is another object of the present invention to provide a toy bank construction which requires the filling of the bank before any coins can be taken from the same and wherein the recording of the coins placed in the bank is given and so that the user of the bank will know the required number of coins that is needed to complete the discharge of the contents of the bank.

Other objects of the present invention are to provide a small cash register or toy bank which is simple in construction, inexpensive to manufacture, has a minimum number of parts, self-discharging upon a predetermined number of coins placed therein, compact, convenient to use and efficient in operation.

For other objects and for a better understanding of the invention, reference may be had to the following detailed description taken in connection with the accompanying drawing, in which:

Fig. 1 is a perspective view of the cash register embodying the features of the present invention.

Fig. 2 is a vertical sectional view taken on line 2—2 of Fig. 1.

Fig. 3 is a fragmentary perspective view looking upon the working parts thereof.

Fig. 4 is a top plan view of certain of the working parts and illustrating the manner in which the coin is received and used to force outwardly a latch which engages a wheel to turn the same.

Fig. 5 is a fragmentary elevational view of the gears which display the registrations, or the amount of deposit.

Fig. 6 is a transverse sectional view taken on line 6—6 of Fig. 5.

Fig. 7 is a fragmentary perspective view of the slide representative of a cash drawer which can be drawn to an open position to discharge the contents of the bank or register when a predetermined amount of money has been placed therein.

Referring now to the figures, 10 represents an exterior casing in which is fitted and secured a top piece 11 with a front extension 12 which extends downwardly over the front of the casing. The casing has a bottom portion 13 in which is an opening 14 through which coins can be dispensed

upon a slide 15 being pulled outwardly from its turned up handle portion 16 representative of a cash drawer. A spring 17 extending between a projection 18 on the slide and a projection 19 on the bottom portion 13, normally maintains the slide in its retracted position and over the opening 14. A stop portion 21 is provided on the rear of the bottom 13.

Within the casing at the front thereof is a vertical wall 22. This partition has an inwardly and horizontally extending supporting portion or partition 23. A slide 24 is adjustable over this supporting portion 23 having downturned legs 24a and 24b and a similar downturned leg 24c, these legs all supporting the slide 24 slidably on the partition 23. A handle 25 projects outwardly from the slide 24 through a slot 26. In the slide is an opening 27 through which a coin can be dropped for support upon the horizontal portion 23. One end of the opening 27, shown at 27b, is rounded, and the opposite end, shown at 27a, is a straight edge. The rounded end 27b of the opening 27 is in registry with a circular opening 28 in the roof 11 of the casing when the slide is in its normal position and held against a stop 29 on the portion 23. The leg 24b which extends partway forward of the slide, has an extension 31a extending forward beyond the front edge of the partition 23, and the extension 31a has an elongated extension 31 at right angles thereto positioned between the forward edge 59 of the partition 23 and the plane of the gear 35. Thus the extension or finger 31 is resilient and yieldable. An elongated upstanding ear 32 on the partition 23 is substantially parallel to the finger 31. The finger 31 has a right-angled forward projection 33. When a coin is deposited on the partition 23 as above described, and by means of the handle 25 the carriage is moved to the right, Fig. 3, the coin rides on the ear 32 and thus presses the finger 31 outward (or forward) to cause the projection 33 to engage with any one of a plurality of teeth 34 angularly spaced upon a wheel 35 pivoted at 36 upon the vertically extending partition 22. As the slide continues its movement, the wheel 36 will be rotated so that a number on the front face of the wheel will be displayed through a hole 37 on the front 11 of the casing. On the slide 24 being released, a spring 38 will return the slide to its initial position. The flexible portion 31 is flexed as may be clearly seen in Fig. 4 by the coin being moved as it rides upon the upstanding projection 32. The coin is indicated at 41 and is moved generally in the direction of arrow 42. The indications on

the front of the wheel 35 will indicate if dimes are placed in the bank, the contents in multiples of ten cents.

On the wheel 35 is a long projection 43 which will engage any of vanes 44 of a wheel 45 pivoted at 46 upon the vertically extending partition 22. Every time the wheel 35 makes a single turn, the wheel 45 will be advanced one step. With five vanes thereon and with dimes being used, the wheel 45 will be moved for each turn of the wheel 35 to give dollar indications through opening 47 in the front of the casing. A zero indication 48 will remain in the front of the casing as the registry of the coins is made in units of ten.

When the wheel 45 has registered five dollars and has made a complete turn, a notch 49 will become aligned with an upstanding projection 51 on one side of the slide 15. The wheel 35 has a single notch 58 positioned between one pair of slots 53, as shown in Fig. 3, adapted to be aligned once during each revolution of the wheel 35, with an upstanding projection 52 on that side of the slide 15 opposite the projection 51. Thus, only when the projections 51 and 52 are aligned with their respective notches 49 and 50 (after five revolutions of wheel 35 and consequently one revolution of wheel 45), is it possible to pull out slide 15 to permit removal of the banked coins through the opening 14. At all other times slide 15 is obstructed by one or both of wheels 35 and 45.

A notch 55, as shown on the left-hand side of the slide, Fig. 3, permits wheel 35 to pass through the upright side of the slide 15. An upstanding spring retainer 56 on the bottom portion engages with the projections 34 on the wheel 35 to properly center the wheel as the same is rotated one step at a time. This spring will hold the wheel against reverse turning movement and its tension is readily overcome as the next coin is dropped into the openings and the slide moved. A vertically extending spring retainer 57 engages with the vanes 44 to hold the wheel 45 properly centered and against displacement and except when acted upon the projection 43 on the wheel 35.

While various changes may be made in the detail construction, it shall be understood that such changes shall be within the spirit and scope of the present invention as defined by the appended claim.

I claim:

A cash register construction comprising a casing having an opening through which a coin can be passed, a supporting structure within the cas-

ing, a slide adapted to receive the coin and having a portion extending through the casing to effect the operation of the slide, said casing having an elongated slot receiving said projection, a counting mechanism adapted to display indications, said casing having opening means through which the indications of the counting mechanism can be displayed, said counting mechanism including a member having projections thereon, said slide having a member adapted to be flexed and having an abutment adapted to engage with the projections of a member of the counting mechanism, a stationary abutment on the internal supporting structure against which the coin can react to force the flexible portion and slide into engagement with the counting mechanism, said movable member of the counting mechanism being in the form of a disc and having projections angularly spaced thereabout, said member being pivotally connected on the vertical supporting structure within the casing, a second disc having angularly spaced projections thereon and pivotally connected to the vertical supporting structure within the casing, said first disc having a projection adapted to engage with the projections of the second disc to, upon one revolution of the first wheel, cause the angular movement of the second wheel, said discs having said indications thereon, a closure slide for normally keeping the coins within the casing, said casing having an opening therein adapted to be closed by the closure slide, said first disc having a notch therein, said closure slide having an upstanding projection on one side thereof at right angles to the plane of said first disc, said closure slide projection having a notch in the upper end thereof and being so positioned on said closure slide that when the latter is closed the edge of said first disc passes through said last-named notch, said upper end of said closure slide projection being adapted to pass through said disc notch when said disc notch has come into registry with the closure slide projection whereby upon a predetermined amount of coins being placed in the casing, whence the closure slide can be operated to release the coins.
